ATTORNEYS

UNITED STATES PATENT OFFICE.

OTTO WHITE, OF KELLOGG, IDAHO.

NAIL.

1,188,868.

Specification of Letters Patent. Patented June 27, 1916.

Application filed December 20, 1915. Serial No. 67,899.

To all whom it may concern:

Be it known that I, OTTO WHITE, a citizen of the United States, and a resident of Kellogg, in the county of Shoshone and State of Idaho, have invented a new and useful Improvement in Nails, of which the following is a specification.

My invention is an improvement in nails, of the character used in boots and shoes, and the invention has for its object to provide a nail of the character specified in the form of a bar adapted to be countersunk or partly countersunk into the material of the outer sole and having at each end a calk extending beyond the outer face of the outer sole and having near each end on the opposite face a pointed spur or lug for piercing the sole of the shoe and for clenching on the inner face of the sole to bind the parts together.

In the drawings:—Figure 1 is a perspective view of a shoe provided with the nails. Fig. 2 is an enlarged section of the sole at one of the nails. Fig. 3 is a perspective view 25 of a nail looking from above. Fig. 4 is a view similar to Fig. 2 of a construction adapted for lighter weight shoes, and Fig. 5 is a perspective view of the nail shown in Fig. 3 in reverse position.

The embodiment of the invention shown in Figs. 2 and 3 is shown in connection with the sole of a shoe, the nails being utilized to connect the upper 1 of the shoe to the insole 2 and the outsole 3, and the nails are preferably arranged from the heel 4 on each side of the shoe, that is, from one side of the heel around the edge of the sole to the other side of the heel. Each nail as shown in Fig. 3, comprises a bar 5 having at 35 each end a spur or calk 6, the spurs or calks extending in the same direction from the bar, and it will be noticed that each of the spurs or calks is rounded and pointed to insure a firm grip on the supporting surface 40 for the shoe. In addition to the spurs or calks 6, the bar 5 has two pointed spurs or lugs 7, extending in the opposite direction from the calks 6, and these lugs or spurs 7 taper more gradually to a point than the 45 calks 6, and the said spurs or lugs are of greater length than the calks. The calks 6 are at the ends of the bar, while the spurs or lugs 8 are spaced inwardly slightly from the ends of the bar, and the bar is cut away 50 at each end on the face adjacent to the spurs or lugs 7 to form a shoulder 8 between each

spur 7 and the adjacent end of the bar, the said shoulders being in the same plane as shown in Fig. 2.

In use when the edge of the upper 1 has 60 been inserted between the insole 2 and the outsole 3 the nails are driven through the soles and the upper and are clenched on the upper face of the insole 2 as indicated at 65 in Fig. 3. That portion of the bar between the calks 6 affords a driving surface for striking with a hammer or other tool to force the spurs 7 through the material of the insole, outsole and upper and when the points of the spurs 7 are clenched as shown, the 70 nail is held firmly in position and could not become displaced.

In the form shown in Figs. 2 and 3 the bar is forced into the material of the outsole as shown, until the outer face of the bar 5 75 is flush with the outer face of the outsole. When so arranged the shoulders 8 engage the sole to assist that face of the bar between the spurs 7 in resisting the further entrance of the bar 5.

In the embodiment of the invention shown in Figs. 4 and 5 the nail consists of a bar 10, having at each end on one face a calk 11, and near each end on the other face a pointed spur or lug 12. In this construction the 85 calks 11 are sharper than the calks 6 of the construction of Fig. 2, and the calks 11 are spaced inwardly a little from the ends of the bar.

In Figs. 2 and 3 the calks are at the ends 90 of the bars while in Figs. 4 and 5 there is a plane surface 13 between each calk and the end of the bar. The upper face of the bar at the outer side of each spur or lug 12 is cut away as indicated at 14 in the same manner as the bar 5 is cut away at 8 in Fig. 2. After the upper 15 has been placed between the insole 16 and the outsole 17 the spurs or lugs 12 are driven through the soles and clenched as shown at 17 on the upper face of 100 the insole.

It will be obvious that if more than one row of nails is desired another row may be arranged outside of the row shown in Fig. 1, the outer row or series of nails being 105 clenched outside of the upper on the upper face of the outsole. With extended soles the nails could be very easily connected with the extension of the sole. It is obvious also that the nails might be connected with the 110 outermost layer of the sole and clenched on this sole before the sole is placed on the shoe.

Since however, the nails serve as a holding means in connecting the upper to the soles and for connecting the soles together it is preferable to arrange them as shown in Figs. 2 and 4. The bar and the calks of the nails are of steel or like hard material so that they will not easily wear away but the lugs 7 and 12 are of malleable or soft material, so that they may be bent to clench without breaking.

Particular attention is called to the fact that the nails cannot kick out. Since there is but one outer sole, that is, one layer of leather in the outer sole, a pound of hob 15 nails would necessarily be put in to make them close enough so that they would not kick out when nailed with the old style of nail.

I claim:—

- 20 1. In a shoe, the combination with an upper and inner and the out soles, the edge of the upper being inserted between the soles, and means for securing the soles to the upper, said means comprising nails, each consisting of a bar having at each end on one face a laterally extending calk and having near each end on the opposite face a laterally extending pointed spur or lug, said spurs or lugs being spaced inwardly from the ends of the bar and the said bar being cut away outside of each of the said spurs or lugs to pro-

vide shoulders at the ends of the bar in the same plane, the spurs or lugs being adapted to be clenched with the face of the bar adjacent to the calks flush with the outer face 35 of the outsole.

2. A nail of the character specified, comprising a bar having at each end of one face a laterally extending calk and having near each end on the opposite face a laterally extending pointed spur or lug, said spurs being spaced inwardly from the ends of the bar and out of alignment with the calks, and the bar being cut away outside of each spur to provide a shoulder at the said end of the 45 bar, said shoulders being in the same plane, and the spurs being adapted to be clenched to hold the nail in place.

3. A nail of the character specified, comprising a bar having on one face laterally 50 extending calks and having near each end on the opposite face a laterally extending pointed spur or lug, said spurs being spaced inwardly from the ends of the bar and out of alignment with the calks, the spurs being 55 adapted to be clenched to hold the nail in place.

OTTO WHITE.
